TELESCOPIC STRUCTURE

Frank W. Odin, Chicago, Ill.

Application June 12, 1944, Serial No. 539,981

7 Claims. (Cl. 287—58)

This invention relates, in general, to telescopic structures, but more particularly to improved means for locking together two telescoping members, at any desired point in their relative adjustment, quickly and effectively.

A further object is to provide an improved clamping or locking means, in which the number of parts will be reduced to a minimum, and which will be effective and efficient in operation.

A still further object is to provide improved locking means of this character, which will be concealed within the telescoping members, and also improved means which will serve to indicate and assist in determining the relative positions of the telescoping members.

To the attainment of these ends and the accomplishment of other new and useful objects as will appear, the invention consists in the features of novelty, in substantially the construction, combination and arrangement of the several parts, hereinafter more fully described and claimed, and shown in the accompanying drawing illustrating this invention, in which

Fig. 1 is a perspective view of a display stand constructed in accordance with the principles of this invention.

Fig. 2 is an enlarged detail view of portions of the telescoping members and of the clamping or locking means.

Fig. 3 is a detail perspective view of a portion of one of the members.

Fig. 4 is a view, partly in elevation and partly broken away, and on an enlarged scale, of the clamping or locking means.

Fig. 5 is a detail sectional view taken on line 5—5, Fig. 4, showing the parts in a clamping or locking position.

Fig. 6 is a view similar to Fig. 5, showing the parts in an unclamping position.

Fig. 7 is a detail sectional view taken on line 1—1, Fig. 4.

Fig. 8 is a view, partly in elevation, partly broken away, and with parts omitted, of a modified form of the invention.

Fig. 9 is a detail sectional view taken on line 9—9, Fig. 8.

Fig. 10 is a detail sectional view of a portion of the locking sleeve, in the form of the invention shown in Fig. 8.

While, in the present exemplification of this invention, the telescopic structure is shown and described as constituting a part of the standard of a display support or stand, it is to be understood that the invention is not to be limited to such use, as it is well adapted for securing to

5 together, in adjusted relation, any telescopic structure to which the invention may be applied.

In Fig. 1, there is shown a display support comprising a base 15 and an upright standard 16, which latter is of tubular construction and is provided with a slot 17 extending through one end thereof, so as to impart resiliency to the standard. A shoulder or projection 18 may be formed at the lower end of the slot 17, for a purpose to be described. The numeral 19 designates a second member, which telescopes into the slotted end of the standard 16 and is of a diameter slightly less than the internal diameter of the standard 16, so as to permit of a longitudinal as well as relative rotary adjustment of one member with respect to the other.

A sleeve 20 encompasses the slotted end of the standard 16, and is provided with an internal projection 21, which latter may be formed in any suitable manner, such as by striking up a portion of the sleeve. When the sleeve is in position upon the standard 16, the projection 21 will stand within the slot 17, so that the sleeve may be moved longitudinally upon the standard.

20 The sleeve 20 is provided with a cut-away portion 22 at its base, so that when the sleeve is in position upon the standard, the projection 18 on the standard will be disposed between spaced shoulders 23, to limit the rotary movement of the sleeve upon the standard. In use, the sleeve 20 is first placed upon the standard 16, with the projection 21 positioned in the slot 17 and with the projection 18 between the shoulders 23, the projection also serving as a means for supporting the sleeve.

30 The member 19 is then inserted into the standard 16 through the sleeve, and is adjusted to the desired height with respect to the standard 16, after which the sleeve 20 is rotated with respect

40 to the standard 16, from the position shown in Fig. 6 to the position shown in Fig. 5. This rotation of the sleeve will cause the projection 21 to engage and depress one edge of the slot 17, so as to contact the slotted end of the standard 16, and thereby cause the same to contract and clamp the standard in its adjusted position. The sleeve may be rotated until one of the shoulders 23 engages the projection 18. To release the member 19 with respect to the standard 16, to

45 permit of further adjustment, the sleeve may be rotated back to the position shown in Fig. 6, and the inherent resiliency of the slotted end of the standard 16 will cause it to expand, and thereby permit adjustment of the member 19.

50 In the form of the invention shown in Figs.

8, 9 and 10, the standard 24 is provided with a slotted end 25, and the walls of the slot are cut away, as at 26, to form resilient projections or fingers 27 which will, by reason of the cut-away portions 26, be spaced from the resilient portions 28. In this form of the invention, the sleeve 29 is provided with two projections 30 extending inwardly from the inner face thereof, and the member 31, corresponding to the member 19, is provided with peripheral recesses 32 spaced lengthwise of the member 31, to form surfaces 33 intermediate the recesses 32.

With this form of the invention, the spring fingers 27 serve the function of indicating the extent of relative adjustment of the telescoping members. When the member 31 is telescoped into the standard 24 and is moved longitudinally thereof, the fingers 27 will enter the recess 32 which is adjacent thereto, and during the relative longitudinal movement of the members, they will successively enter the recesses 32 as the latter are moved adjacent the fingers. This will serve either as a visual or an audible indication of the extent of such relative adjustment.

After the desired adjustment has been obtained, the sleeve 29 may be rotated with respect to the standard, and one of the projections 30 will force the portions 28 of the standard against one of the surfaces 33, while the other projection 30 will force one of the fingers 27 into and against the bottom of one of the recesses 32, and thereby frictionally clamp the parts in position. To unclamp the member 31, the sleeve is rotated to a position so that the projections 30 will stand within the slot 25, and in such position the sleeve may be moved longitudinally of the standard.

While the preferred forms of the invention have been herein shown and described, it is to be understood that various changes may be made in the details of construction and in the combination and arrangement of the several parts, within the scope of the claims, without departing from the spirit of this invention.

What is claimed as new is:

1. In combination, two telescoping members, the outermost member having an elongated slot extending through one end thereof to impart resiliency to said end, a sleeve encompassing and mounted thereupon for rotation and for lengthwise movement with respect to said slotted end, and a projection on the inner face of the sleeve, adapted to be positioned to extend into said slot, whereby upon rotation of said sleeve said projection will move out of the slot to contract said slotted end to clamp the inner member, said projection being also movable along said slot when positioned therein and when said sleeve is moved lengthwise of said slotted end.

2. In combination, two telescoping members, the outermost member having an elongated slot extending through one end thereof to impart resiliency to said end, a sleeve encompassing and rotatable upon said slotted end, and a projection on the inner face of the sleeve adapted to be positioned to extend into said slot, and to be rotatably moved out of the slot to contract said slotted end to clamp the inner member, said projection being movable along said slot when positioned therein and when said sleeve is moved lengthwise of said slotted end, said sleeve and said slotted end being provided, one with spaced stops and the other with a projection movable between said stops to limit the rotation of said sleeve.

3. In combination, two telescoping members,

the outermost member having an elongated slot extending through one end thereof to impart resiliency to said end, a sleeve encompassing and rotatable upon said slotted end, a projection on the inner face of the sleeve adapted to be positioned to extend into said slot, whereby upon rotation of said sleeve said projection will contract said slotted end to clamp the inner member, said projection being movable along said slot when said sleeve is moved lengthwise of its supporting member, and automatically operable interengaging means on said members for indicating the extent of relative adjustment of said members, a portion of said indicating means being movable in directions lengthwise of one of said telescoping members.

4. In combination, two telescoping members, the outermost member having an elongated slot extending through one end thereof to impart resiliency to said end, a sleeve encompassing and rotatable upon said slotted end, a projection on the inner face of the sleeve adapted to be positioned to extend into said slot, and when upon rotation of said sleeve said projection will contract said slotted end to clamp the inner member, said projection, when positioned in said slot, being movable along said slot when said sleeve is moved lengthwise of its supporting member, additional interengaging means on said members for indicating the extent of relative adjustment of said members, the said means embodying a resilient finger on one of said members, and a series of spaced annular recesses arranged lengthwise of the other member, for successively receiving said finger, as one of the members is moved lengthwise of the other.

5. In combination, two telescoping members, the outermost member having an elongated slot extending through one end thereof to impart resiliency to said end, a sleeve encompassing and rotatable upon said slotted end, a projection on the inner face of the sleeve extending into said slot, whereby upon rotation of said sleeve said projection will contract said slotted end to clamp the inner member, said projection moving along said slot when said sleeve is moved lengthwise of its supporting member, interengaging means on said members for indicating the extent of relative adjustment of said members, the said means embodying a resilient finger on one of the members engageable in recesses on the other member, and a projection on said sleeve for forcing said finger into one of said recesses.

6. In combination, two telescoping members, one of said members having an elongated slot extending through the end thereof, the edge of said slot being cut transversely of the length of the member to form resilient portions spaced lengthwise of the member, the other of said members having recesses spaced lengthwise thereof, a sleeve encompassing the slotted member, and projections on the inner face of said sleeve, said projections extending into and movable in the slot when said sleeve is moved lengthwise of said slotted member, said projections operating respectively, when said sleeve is rotated upon said slotted member, to force one of said resilient portions against a portion of one of the telescoping members between said recesses, and another resilient portion into one of said recesses.

7. In combination, two telescoping members, one of said members having an elongated slot extending through the end thereof, the edge of said slot being cut transversely of the length of the member to form resilient portions spaced

lengthwise of the member, the other of said members having recesses spaced lengthwise thereof, a sleeve encompassing the slotted member, and projections on the inner face of said sleeve, said projections extending into and movable in the slot when said sleeve is moved lengthwise of said slotted member, said projections operating respectively, when said sleeve is rotated upon said

slotted member, to force one of said resilient portions against a portion of one of the telescoping members between said recesses, and another resilient portion into one of said recesses, the said recesses and the co-operating said resilient portions serving to indicate the extent of longitudinal relative movement of said members.
